(57) **CLAIM**

We claim the ornamental design for an aftertreatment system component with integrated support rods, as shown and described.

DESCRIPTION

FIG. 1 is a front view of the aftertreatment system component with integrated support rods according to an embodiment of our new design;

FIG. 2 is a rear view of the embodiment;

FIG. 3 is a left side view of the embodiment;

FIG. 4 is a right side view of the embodiment;

FIG. 5 is a top view of the embodiment;

FIG. 6 is a bottom view of the embodiment; and,

FIG. 7 is a front, right, top perspective view of the embodiment.

The ornamental design that is claimed is shown in solid lines in the drawings. The broken lines in the drawings depict environmental subject matter only and form no part of the claimed design.
